UNITED STATES PATENT OFFICE.

DEWITT G. GARLOCK, OF WHITE CLOUD, KANSAS.

IMPROVEMENT IN HARNESS-MAKERS' GAGES.

Specification forming part of Letters Patent No. 135,472, dated February 4, 1873.

To all whom it may concern:

Be it known that I, DEWITT G. GARLOCK, of White Cloud, in the county of Doniphan and State of Kansas, have invented a new and useful Improvement in Harness-Maker's Gage, of which the following is a specification:

The object of this invention is to furnish improved means for cutting leather and similar material into strips; and it consists in the screw for moving the head and handle of the gage, with device for holding the same stationary; and in the combination of the screw with the gage-bar, all shown in the drawing and hereinafter described in this specification.

Figure 1 is a view of the reverse side of the gage. Fig. 2 is a longitudinal section, taken on the line *x x* of Fig. 1. Fig. 3 is a sectional top view, and Fig. 4 represents a section taken on the line *y y* of Fig. 1.

Similar letters of reference indicate corresponding parts.

A is the gage-bar. B is the cutter-head, in which is the knife or cutter C, fastened by the thumb-screw D. E is the movable gage-head and handle, through which the gage-bar passes. F is a screw, one end of which enters the cutter-head, as seen at G. The other end is attached to the opposite end of the gage-bar by the box H. This screw passes through the gage-head E, and works therein as through a nut. The screw revolves, but is secured, by means of a shoulder and the finger-wheel I, in the box H, so that it has no longitudinal motion.

It will be seen that when the screw is revolved the gage-head will be moved, and may be set in any desired position.

J represents a series of holes in the finger-wheel I. This wheel is on the end of the screw outside of the box H. K is a slotted bolt, which is made to slide on the gage-bar, the end of which enters one of these holes in the wheel when the gage-head is adjusted, and thereby holds the screw and head stationary. This bolt is confined to the under side of the bar by means of a slot and screw and the box H, through which the bolt passes.

This is a great improvement over the gage now in use, and its advantages will be readily understood and appreciated by all who are engaged in harness-making, and in all operations where it is necessary to cut leather or similar material into strips of uniform width.

Having thus described my invention, I claim as new and desire to secure by Letters Patent—

The gage-head E, combined with the screw F, swiveled in cutter-head B, and provided with the perforated finger-wheel I J, and the gage-bar having slotted sliding bolt K, arranged as and for the purpose described.

DEWITT G. GARLOCK.
